UNITED STATES PATENT OFFICE.

GEORGE SCOTT CHILES, OF CHICAGO, ILLINOIS.

CAR TRUCK.

Application filed May 15, 1922. Serial No. 561,133.

To all whom it may concern:

Be it known that I, GEORGE SCOTT CHILES, a citizen of the United States, and a resident of Chicago, in the county of Cook and State 5 of Illinois, have invented certain new and useful Improvements in Car Trucks, of which the following is a specification.

The invention described and claimed herein is a modification of the inventions more 10 generically claimed in my copending applications, Serial No. 470,465, for railway truck construction, filed May 17, 1921, Serial No. 516,554, for trucks, filed November 21, 1921, and my application Serial No. 15 561,132, for railway trucks, executed of even date herewith.

My invention broadly stated consists in my improved grouping of the truck springs and an improved side-frame, bolster and 20 spring plank coating with the improved spring assemblage. In the copending applications above referred to, I have described and claimed applications of my invention wherein the springs are placed between the columns of the side-frame, the side-frame having a central bolster opening. In the modification herein described, I construct the side-frame with a single central column connecting the tension and compression members, divide the springs into two groups, one on each side of the central column, and form the bolster and spring plank, when a spring plank is used, with divided ends embracing the central column. In the 30 form of my invention herein described, I preferably construct the tension member in the form of a suspension line curve; that is, with the cross-sectional center of mass of the tension member lying substantially in a 35 suspension line throughout the length of said member. The suspension line upon which the tension member is constructed is the curve which would be assumed by a flexible member, such as a cable or chain suspended at its ends and with a vertical load of the magnitude and distribution to which the side-frame is subjected. The use of the 40 suspension line form of tension member throws substantially all of the vertical load 45 stress in that member into tension, thereby eliminating bending stresses and rendering it possible to lighten the frame. In my improved spring assemblages, the springs are distributed endwise of the side-frame more 50 widely than in assemblages now in use, and this wider distribution of the springs has

two advantageous results. It affords a wider support for the end of the bolster, thereby affording increased resistance to tilting forces imposed upon the bolster, and the wider distribution of the springs also gives a flatter form of resultant suspension curve than would be obtained by concentrating the springs at the center of the side-frame as with the present type of construction. This flattening of the suspension line increases the vertical distance between the tension and compression members intermediate the center and ends of the side-frame, thus affording more ample head room for the end springs of the assemblage. The adoption of the suspension line form of tension member and the resultant throwing of the stresses into tension, gives greater latitude in adapting the cross-sectional form of the tension member to the accommodation of the springs and bolster than is possible when the tension member is subjected to severe bending stresses. The bending stresses to which types of side-frames now in use are subjected necessitate a relatively great vertical cross-sectional depth in the tension member, which depth, taken in connection with the necessary road clearance, imposes a limitation upon the depth of the bolster opening, and consequently upon the depth of the bolster end. With the tension member in the form of a suspension line and the stresses substantially all in tension, the vertical depth of the tension member may be much less than in the forms of construction now in use, and the height of the bolster opening may be correspondingly increased. The necessary tensile strength in the tension member is preserved by increasing its width transversely of the side-frame, the increased width affording space for proper seating of the springs without the extent of overhang necessary in the present form of side-frames. The transverse widening of the tension member also serves the purpose of increasing the resistance offered to transverse and twisting forces imposed upon the frame in service. The increased vertical height of the bolster opening also admits of constructing the bolster end of greater vertical depth, thereby securing the necessary strength with less metal. The saving in weight in both side-frame and bolster increases with the increase in the capacity of the cars. All of the foregoing applies to side-frames having two columns with the

springs between the columns, and to side-frames of the form herein described and claimed wherein a column is placed at the center. Other advantages of my improved construction will appear from the following description of a specific embodiment of my invention.

In the drawings, Figure 1 is a view in elevation of a side-frame, bolster, springs and spring plank embodying my invention, the structure illustrated being broken away at one end to admit of a larger scale drawing,

Figure 2 is a top plan view of the structure shown in Figure 1,

Figure 3 is a view from beneath of the structure shown in Figure 1, and

Figure 4 is a top plan view of the end of the bolster.

I have shown in the drawings an integral side-frame designed to receive separable journal boxes, but it will be apparent that my invention is not limited to a side-frame of that type or to integral side-frames. In the form of side-frame illustrated, the compression member 1 may be of channel form. The tension member may be of similar or other suitable form down to about the point indicated by the numeral 2. In the specific form illustrated, the tension member is of channel section and the cross-sectional center of mass of the tension member throughout its length between its point of suspension over the journal boxes lies substantially in the suspension line curve that would be assumed by a flexible member subjected to the vertical load for which the side-frame is designed. As illustrated, the compression and tension members are connected at the center of the side-frame by a vertical column 3. I have illustrated an assemblage of six springs divided into groups of three each, one group upon each side of the central column 3. The two springs adjacent the columns are arranged abreast; that is, in a pair transverse of the side-frame, and the third spring is placed substantially upon the longitudinal center line of the side-frame. In this embodiment of my invention, as in all forms of my improved spring assemblage, the outermost ends of the spring assemblage consist of single springs upon or adjacent to the longitudinal center line of the side-frame.

By having single springs 4 at each end of the assemblage, I am better enabled to maintain the suspension line and also the necessary vertical space between the spring seat and bolster. The spring seat takes the form of a web which is so disposed with relation to the remainder of the section as to maintain the cross-sectional center of mass substantially in a suspension line. This web begins at the upper edges of the side walls of the channel section which forms the end portions of the tension member at the point

indicated by the numeral 2, and continues across the center of the side-frame to a corresponding point at the other end. At the central part 5 of the side-frame the spring seat joins the upper edges of the side walls of the tension member. At 6 the spring seat rises above the side walls of the tension member, and is then continued horizontally at 7 to a point 8 midway of the height of said side walls, from which point the web forming the spring seat rises as indicated at 9 to the upper edges of the side walls into which it merges as indicated at 10-10 in Figure 3. The portion 7 of the spring seat lies at a lower level than part of the transversely adjacent metal of the side-frame, the lower part of the end springs 4 being thus recessed in the tension member. This permits the tension member to follow the suspension line at this point without interfering with the space necessary for the end springs.

The bolster and spring plank are recessed at their ends as indicated at 11 and 12 to embrace the column 3. The two central pairs of springs 13-13 lie under the main portion 14 of the bolster, which is provided with extensions 15 of less depth than the central portion, said projections resting on the end springs 4. In the present instance, I have shown the spring plank 16 underlying the four central springs only and provided with upwardly projecting side walls 17 which are offset inwardly at 18 to permit closer spacing of the springs.

While I have herein illustrated and described a specific embodiment of my improved truck construction, my invention is not limited thereto, but may be varied within the limits defined in the following claims:

1. In a car truck, a side-frame comprising an upper compression member, a lower tension member, a column connecting said compression and tension members at the central part thereof, springs supported on said tension member on each side of said column, some of said springs being offset from the longitudinal center line of said side-frame.

2. In a car truck, a side-frame, springs, a bolster supported on said springs, said bolster being recessed at the end, part of said springs being in each side of said recess.

3. In a car truck, a side-frame comprising an upper compression member, a lower tension member, the cross-sectional center of mass of said tension member throughout its length lying substantially in a suspension line curve, and a column connecting said compression and tension members at the central part thereof.

4. In a car truck, a side-frame comprising an upper compression member, a lower tension member, the cross-sectional center of mass of said tension member throughout its

length lying substantially in a suspension line curve, and a column connecting said compression and tension members at the central part thereof, springs supported on said 5 tension member on each side of said column, and a bolster resting on said springs and having a recess in its end embracing said column.

5. In a car truck, a side-frame comprising 10 an upper compression member, a lower tension member, a column connecting said compression and tension members at the central part thereof, a group of springs supported on said tension member on each side of said 15 column, the part of each of said groups of springs most remote from said column consisting of a single spring.

6. In a car truck, a side-frame comprising 20 an upper compression member, a lower tension member, the cross-sectional center of mass of said tension member throughout

its length lying substantially in a suspension line curve, a column connecting said compression and tension members at the central part thereof, and a spring plank 25 resting on said tension member and having a recess in its end embracing said column.

7. In a car truck, a side-frame comprising an upper compression member, a lower tension member, and a column connecting said 30 compression and tension members at the central part thereof, a group of springs supported on said tension member on each side of said column, the part of each of said groups of springs most remote from said 35 column consisting of a single spring, and a spring plank resting on said tension member and having a recess in its end embracing said column.

In witness whereof, I hereunto subscribe 40 my name this 12th day of May, A. D., 1922.

GEORGE SCOTT CHILES.
